Primary Examiner — Lauren R Calve

(57) **CLAIM**

The ornamental design for a combined protective case and hanger for wire, as shown and described.

DESCRIPTION

FIG. 1 is a front elevational view of a combined protective case and hanger for wire showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines shown represent portions of the combined protective case and hanger for wire and environmental features that form no part of the claimed design.

1 Claim, 7 Drawing Sheets
